UNITED STATES PATENT OFFICE.

ISAAC DE GOWIN, OF NEW HAVEN, CONNECTICUT, ASSIGNOR TO THE SEAMLESS RUBBER COMPANY, INC., OF NEW HAVEN, CONNECTICUT, A CORPORATION OF MASSACHUSETTS.

BALL.

1,423,837.

Specification of Letters Patent. Patented July 25, 1922.

Application filed April 23, 1920. Serial No. 376,165.

To all whom it may concern:

Be it known that I, ISAAC DE GOWIN, a citizen of the United States, and a resident of New Haven, county of New Haven, and

5 State of Connecticut, have invented an Improvement in Balls, of which the following description, in connection with the accompanying drawings, is a specification, like characters on the drawings representing

10 like parts.

This invention relates to balls and more particularly to that type of ball which has applied thereto a covering of felt. The tennis ball is a well known example. The 15 object of this invention is to provide a ball having a novel form of covering which will be durable and substantial and a method whereby the covering may be applied.

My invention will best be understood by 20 reference to the following description taken in connection with the accompanying drawings wherein I have shown diagrammatically various exemplary mechanisms adapted for use in producing the ball covering and

25 wherein:

Fig. 1 is a diagrammatic sectional view of a bat-forming mechanism;

Fig. 2 is a similar view of a blocking or pressing mechanism; and

30 Fig. 3 is a partially broken elevation of the completed ball.

My invention may be conveniently explained by describing the method whereby the cover is produced, referring in the course 35 of the description to mechanisms which may be used in carrying out the method. Reference to these particular mechanisms shown herein diagrammatically is, however, merely to facilitate the understanding of

40 the description.

Referring to Fig. 1 I have there shown a bat-forming machine embodying a rotary perforated cone 5 from the interior of which air is exhausted by the revolving fan 7.

45 Adjacent the cone is the tunnel 9 into which are introduced suitable felting fibers which are agitated and thrown toward the cone by the rotary brush 11. The cloud of felting fibers is sucked on to the cone by

50 the draft produced by the fan 7 and deposited thereon to form a conical felted layer or bat. The bat of felted fibers which is thus formed may then be fulled by treatment in a suitable fulling liquid and

55 mechanically manipulated in any desired

manner to toughen and thicken it. The operations sometimes known as basoning and planking do not require extended description in this place.

The fulled section which at this stage 60 should approximate one-half the size of the ball which is to be covered is then blocked or pressed into hemispherical form and in Fig. 2 I have shown a section 13 pressed by means of a flexible diaphragm 15 into 65 a hemispherical mold 17 which is heated by steam in the chamber 19, the diaphragm being pressed down by hydraulic pressure of water forced into the chamber 21.

By the methods just described or their 70 equivalents there are produced molded felt sections of hemispherical form, each of one-half the size of the ball center which is to be covered. The sections are then coated on the inside with a suitable cement, the ball center, 23 in Fig. 3, is also preferably so coated and two sections are placed over the center, as shown in Fig. 3, with their edges meeting. The parts thus assembled are then placed in a heated 75 mold and are subjected to pressure and heat, smoothing out the cover sections 13 and firmly securing them to the ball center 23.

The completed ball will then appear as in Fig. 3 covered with two hemispheres of 80 felt. This covering has a comparatively short seam or line of junction between the sections as compared with the covering methods usually employed and since the parts are formed from the fibers directly 85 into the form of the ball they are in equilibrium and have no tendency to lift and break away from the center 23. If desired, the sections 13 may be stitched together along their meeting edges but this 90 is not necessary, the forming of the sections as described particularly facilitating their being maintained in position merely by the use of a suitable adhesive on the ball center.

Having described in detail a particular 100 embodiment of my invention and one method by which it may be carried out, the principles illustrated thereby which I claim as new and desire to secure by Letters Patent I shall express in the following claims. 105

Claims:

1. A ball comprising a center and a covering of felt sections secured thereto, each having an inherent form corresponding to part of the sphere. 110

2. A ball comprising a center and molded hemispherical felt sections secured thereto.
3. The methods of covering balls comprising felting fibers to provide cones, blocking the cones to hemispherical form to fit the ball center and adhesively securing them thereto.

4. The method of covering balls comprising felting fibers to provide cones, fulling 10 the cones, blocking them to hemispherical form to fit the ball center and adhesively securing them thereto.

In testimony whereof, I have signed my name to this specification.

ISAAC DE GOWIN.
